UNITED STATES PATENT OFFICE.

JAY B. RHODES, OF HARVEY, ILLINOIS.

DUMP-CAR.

SPECIFICATION forming part of Letters Patent No. 723,921, dated March 31, 1903.

Application filed October 6, 1902. Serial No. 126,077. (No model.)

To all whom it may concern:

Be it known that I, JAY B. RHODES, a citizen of the United States of America, and a resident of Harvey, Cook county, Illinois, have 5 invented a certain new and useful Improvement in Dump-Cars, of which the following is a specification.

My invention relates to dump-cars of the class in which a tilting body is mounted on a 10 truck and provided at each side with a gate or displaceable side-board which automatically opens when the body tilts to one side.

Generally stated, the object of my invention is to provide a simple, compact, and comparatively inexpensively constructed dump-car of the foregoing character.

A special object is to provide an improved form of prop for opening the gates or side-boards.

20 Another object is to provide an improved form of locking device for connecting the lower ends of the said props with the truck.

A further object is to provide an improved form of connection between the side-boards 25 and the body whereby the lower edge of either board may be unlocked or released before the displacement is produced, so as to permit the bottom of the board to first swing outward.

It is also an object to provide certain 30 tails and features of improvement tending to increase the general efficiency and serviceability of a dump-car of this particular construction.

To the foregoing and other useful ends my 35 invention consists in matters hereinafter set forth and claimed.

In the accompanying drawings, Figure 1 is 40 an end view of a dump-car constructed in accordance with my invention. Fig. 2 is a side elevation of the car shown in Fig. 1.

As thus illustrated my improved dump-car comprises a truck A and a tilting body B, mounted thereon. The said body is provided with a pair of oppositely-arranged displaceable side-boards C. Each side-board is connected with the body by a pair of swinging arms c. These swinging arms have their inner ends pivoted at c', while their outer ends are pivoted to the upper ends of the 45 locking-bolts C'. These bolts are arranged for vertical sliding movement in the straps or bearings c². The lower end of each bolt is adapted to engage an opening b in the floor of the body. The props D have their upper ends pivotally secured to the arms c, while 50 their lower ends are adapted to rest upon the truck. Each prop consists of a pair of bars connected at their lower ends by a pin or bolt d. Thus the lower ends of each pair of bars are adapted to straddle the ridge of a short 55 length of T-iron E. The upper end of each inner bar is provided with a bent portion d', adapted to project over the upper edge of the body. Each T-iron is provided with a link e, and these links are adapted to be engaged 60 by the hooks d², mounted on the bolts or pins d. These hooks are adapted to be clamped to the props by means of the sliding rings e². When the body tilts to one side, as shown in Fig. 1, the props at the side to which the 65 body is tilted rest upon the truck between the bolt-heads e', while the props at the other side are lifted upward away from the truck. The props resting on the truck cause the 70 arms and the locking-bolts at that side to remain stationary, while the body and side-board move downward. The initial movement of the body and the side-board is sufficient to disengage the lower ends the bolts 75 from their sockets in the body, and at this 80 point in the operation the stops c³ on the bolts engage the straps c², so as to prevent further relative movement between the side-board and the two bolts. The tilting movement now continuing, the body moves downward 85 away from the side-board, allowing the contents of the body to discharge or dump, at the side of the truck. It will be seen, however, that the instant the two bolts are 90 disengaged from their sockets in the body the side-board is free to swing outward at its bottom, so as to relieve the pressure on its inner surface and so as to permit a partial discharge before the body moves downward 95 relatively to the side-board. In this way the partial tilting movement of the body serves to disengage the lower edge of the board before any relative displacement is produced 100 between the board and the side of the box or body. In other words, the gate or side-board is unlocked and allowed to swing outward before any relative sliding movement is produced between its inner surface and the load. This improved method of operation is exceed-

- ingly advantageous when sharp-edged rocks constitute the load or contents of the body. Before tilting the body to either side it will be readily understood that the locking devices—
 5 that is to say, the hooks d^2 —at the other side must be disengaged, so as to allow one side of the body to rise while the load is being discharged at the opposite side. Inasmuch as the props when unlocked hang pendent with free
 10 lower ends, it follows that either side-board can be swung up and over and allowed to rest upon the opposite side of the body. This, it will be seen, permits either gate to be opened, so as to facilitate loading. Preferably the props do not quite rest upon the truck when the body is horizontal, as shown in Fig. 1. In this way the construction affords a slight play or lost motion between the props and the truck.
 15 20 The short lengths of T-iron are preferably bolted to the sills α by means of the bolts a' . The heads of these bolts, as previously explained, are preferably arranged in such manner as to provide seats for the lower ends of
 25 the bars constituting the props. Thus each prop when pressed down upon the truck has its lower end firmly held against slip or displacement.

With respect to the general operation of
 30 the car it will be seen that the locking-bolts have a positive connection with the props through the medium of the swinging arms, but have a shifting or sliding connection with the side-boards. Hence the locking devices
 35 are operated by the initial tilting movement of the body and act to release the boards before any displacement is produced—that is to say, the boards are allowed to swing outward while moving downward with the load. Thus
 40 the load has no downward-sliding movement relatively to the board whatever, and in this way there is no danger of breakage, particularly in the case of a load consisting of sharp-edged rock. In other words, the locking devices act to release the boards before the
 45 floor of the body is lowered away from their edges.

The locking devices for the lower ends of the props are, it will be seen, adapted to serve
 50 as the sole medium of connection between the truck and the lower ends of said props. In this way these locking devices are capable of totally disconnecting the lower ends of the props from the truck.

55 5. What I claim as my invention is—

1. A dump-car, comprising a truck and a tilting body mounted thereon, displaceable side-boards, props for producing the displacement, and sliding connections intermediate
 60 of the props and side-boards, whereby either board is free to have a slight downward movement with the body before the displacement is produced, and locking devices applied to the lower edges of said boards and adapted
 65 to release the latter during the sliding movement between the props and boards, whereby

either board is unlocked before any displacement takes place.

2. A dump-car, comprising a truck and a tilting body mounted thereon, displaceable side-boards, locking devices for locking the lower edges of said boards against outward movement relative to the body, props for producing the displacement, positive connections between said locking devices and said props,
 75 and sliding connections intermediate of said props and boards, whereby said devices are unlocked before any displacement is produced.

3. A dump-car, comprising a truck and tilting body, a displaceable side-board, locking-bolts mounted to slide on the ends of said board and adapted to engage sockets on the body, swinging arms having their inner ends pivoted to the body and their outer ends pivotally connected with said bolts, and props extending between said arms and the truck and adapted to produce the desired displacement.
 80 85

4. A dump-car, comprising a truck and tilting body, a displaceable side-board, locking devices for normally holding the lower edge of said board against outward movement relatively to the body, props for producing the displacement, positive connections between
 90 said props and said locking devices, and sliding connections intermediate of said props and board, whereby said devices are unlocked and the lower edge of the board allowed to swing outward before any displacement is produced.
 95

5. A dump car, comprising a truck and tilting body, a displaceable side-board, suitable supporting structures for producing the displacement, locking-bolts mounted on said board and suitably connected with said supporting structures, and suitable shifting connections between the bolts and side-board whereby the lower edge of said board is released and allowed to swing outward before any displacement is produced.
 105 110

6. A dump-car, comprising a truck and tilting body, displaceable side-boards, swinging arms connecting said body with said side-boards, props for producing the displacement,
 115 the lower ends of said props being adapted to hang free, and locking devices for connecting the lower ends of said props with said truck.

7. A dump-car, comprising a truck and tilting body, a displaceable side-board, props for producing the displacement, said props being adapted to hang pendent with their lower ends free.
 120

8. A truck and tilting body, a pair of displaceable side-boards, and props suitably connected for producing the displacement, said props being adapted to normally hang pendent with their lower ends free.
 125

9. A dump-car, comprising a truck and tilting body, a pair of displaceable side-boards, props connected to produce the displacement,
 130

and adapted to hang pendent with their lower ends free, and locking devices for locking the lower ends of said props to the said truck.

10. A dump-car, comprising a truck and 5 tilting body, a pair of displaceable side-boards, props connected to produce the displacement, said props being adapted to hang pendent with their lower ends free, links on the said truck, hooks on the props adapted to engage 10 said links, and sliding rings on the props for locking the hooks in engagement with the links.

11. A dump-car, comprising a truck and tilting body, a pair of displaceable side-boards, 15 props connected to produce the displacement, said props being adapted to hang pendent with their lower ends free, T-irons bolted to the truck and adapted to receive the lower ends of said props, links secured to said T- 20 irons, hooks on the props adapted to engage said links, and sliding rings on the props adapted to lock the hooks in engagement with the links.

12. A dump-car comprising a tilting body, 25 a truck upon which said body is mounted, a pair of displaceable side-boards, props connected and arranged to produce the desired displacement of either board when the body is tilted to one side, and locking devices adapted 30 to normally connect the lower ends of said props with said truck, but adapted when unlocked to totally disconnect the props from the truck.

13. A dump-car comprising a suitable truck, 35 a tilting body mounted thereon, a pair of displaceable side-boards for normally closing the sides of said body, suitable members for producing the desired displacement of either board when the body is tilted to one side, and 40 locking devices operated by the initial tilting movement of the body and acting to release the lower edges of the boards before any displacement of the latter is produced.

14. A dump-car comprising a suitable truck, 45 a tilting body mounted thereon, a displaceable side-board for normally closing the side of said body, suitable members for producing the desired displacement of the board when the body is tilted to one side, pivotal connections intermediate of said members and the 50 upper portion of said board, and one or more

locking devices connected and arranged to be operated by the initial tilting movement of the body and adapted to release the lower edge of said board before any displacement of the latter is produced. 55

15. A dump-car comprising a suitable truck, a tilting body mounted thereon, a displaceable side-board for normally closing the side of said body, props connected and arranged 60 to produce the desired displacement of said board when the body is tilted to one side, and locking devices normally serving as the sole means of connection between said props and said truck, but adapted when unlocked to totally disconnect the props from the truck. 65

16. A dump-car comprising a suitable truck, a tilting body mounted thereon, a pair of displaceable side-boards for said body, props suitably connected and arranged for producing the desired displacement of either board 70 when the body is tilted to one side, and locking devices for normally connecting the lower ends of said props to the truck and adapted to serve as the sole medium of connection between the truck and the lower ends of said props. 75

17. A dump-car comprising a suitable truck, a tilting body mounted thereon, a displaceable side-board mounted to swing at its upper end, props for producing the desired displacement of the board when the body is tilted to one side, sliding connections intermediate of the boards and props adapted to allow the board to have a slight downward movement 85 with the body before any displacement of the board is produced, stop devices for limiting the downward movement of said board, and locking devices for normally holding the lower edge of said board in engagement with the 90 body and adapted to automatically unlock and release the board prior to the displacement or relative movement produced between the board and body by said props and stop devices. 95

Signed by me at Chicago, Cook county, Illinois, this 29th day of September, 1902.
